JOSEPH MOTTE, OF TOURCOING, FRANCE, ASSIGNOR TO SOCIETY ETABLISSEMENTS MOTTE-DEWAVERIN, OF TOURCOING, FRANCE, A CORPORATION OF FRANCE

PRESSURE ROLLER FOR SPINNING MACHINES AND THE LIKE

Application filed August 22, 1929, Serial No. 387,675, and in France October 15, 1928.

This invention relates to improvements in and modifications of the invention claimed in my U. S. Patent No. 1,742,553, dated Jan. 7, 1930.

5 The object of the present invention is to provide modifications in the devices forming the subject of the said patent with a view to simplifying and cheapening the construction.

10 These modifications are described herein-after and are illustrated diagrammatically in the accompanying drawing in which:

15 Figure 1 is a fragmentary view in longitudinal section of an apparatus constructed in accordance with the invention.

Figure 2 is a detail view in plan showing the guide limiting the displacements of the loose boss roller.

20 In these figures, 1 is the loose boss roller and 2 the shaft terminating in a guide in the frame. 4 is the spherical ball bearing inserted between the shaft 2 and the loose boss roller 1. On the sleeve 5 is keyed a disc 10 which is made rigid with the loose boss roller

25 1 by being clamped between two rings 11 so that the sleeve 5 follows the movement of rotation of the loose boss roller 1. In order to limit the displacements permitted by the spherical joint mounting simply to the plane 30 passing through the axes of the top and drawing rollers, the guiding device employed comprises a recess 12 provided on the back part of the head 3 and in which the end of the sleeve 5 can turn freely and slide in the said 35 single plane.

It is clearly understood that without going outside the scope of the invention modifications of details may be made along the same lines.

40 What I claim is:

In a top roll for spinning frames, a shaft, a roller on said shaft, a bearing unit interposed between said shaft and roller, a sleeve extending coaxially with said roller, a disc secured to said sleeve and to said roller where-

by said sleeve and roller rotate in unison, and a head on said shaft having a recess for receiving one end of said sleeve and guiding the same.

In testimony whereof I affix my signature. 50
JOSEPH MOTTE.
